UNITED STATES PATENT OFFICE.

GEORGE J. HILL, OF BUFFALO, NEW YORK.

DATING-MACHINE.

Specification forming part of Letters Patent No. 28,861, dated June 26, 1860.

To all whom it may concern:

Be it known that I, GEORGE J. HILL, of the city of Buffalo and State of New York, have invented certain new and useful Improvements in Dating-Machines for Stamping Names and Dates upon Railroad-Tickets; and I do hereby declare that the following is a full, clear, and exact description of the same, reference being had to the accompanying drawings and the letters of reference marked thereon, in which—

Figure I is a vertical section of my improvement. Fig. II is a plan of a portion of the same.

Letters of like name and kind refer to like parts in each of the figures.

A is the bottom or main supporting-plate of the machine, underneath which the inking-rollers are supported. A portion of this plate is cut away to form a space or recess for the type-bed B.

C represents a type-holder, and D type (or it may be a stereotype-plate) therein, which is placed in the type-bed, and is removable therefrom at pleasure. The face of the type as placed will be slightly below the surface of the surrounding plate A. When the type-holder (and type) is placed within the type-bed, it may be held in place by the catch or spring O. This catch is represented in Fig. II as thrown up from the type-holder, and the type-holder is represented as partly drawn out from the type-bed.

E is a roller placed directly under the type-bed. Its diameter is greater than the width of the type-bed. It revolves the type-apron, and serves also the purpose of an inking-roller.

ff are small rollers arranged on either side of the type-bed.

G is an endless apron, of silk ribbon or other suitable material, which passes over the small rollers ff and large roller E, and consequently revolves around and over the type and type-bed, that part of the apron between the rollers ff being parallel with and over the face of the type and nearly in contact therewith, so that the apron will intervene between the face of the type and the card or ticket to be stamped.

H is the platen attached to the end of the vertically-moving rod I, the downward motion

of which is given by the hand of the operator, the coiled spring J raising it again to its highest position.

K is an inking-roller, upon the end of which is placed the ratchet-wheel L.

M is a bent lever having a fulcrum at m' and a pawl N catching into the teeth of the ratchet-wheel L. The platen in its upward movement strikes the opposite end of the lever, and through the pawl and ratchet-wheel causes a movement or partial turn to the inking-roller K, which, through the intermediate roller K', gives motion to the roller E, and hence to the endless apron G. The lever is brought back when the platen descends and the pawl caused to catch another tooth of the ratchet-wheel by the spring P.

W is a bent beam, which rises from the plate A and overhangs the type-bed for the support of the lever M, rod I, spring J, and platen H.

The operation is as follows: The ticket or card to be dated or stamped is laid upon the endless apron G and over the face of the type. The operator strikes the enlarged head of the rod I with a quick blow, and thereby causes the platen to descend upon the ticket or card. The type-apron G has become sufficiently inked by its contact with the inking-rollers E and K', and when the blow of the platen depresses the apron upon the type the type raises such portions of the apron as lie immediately upon the face of the type and force the same upon the ticket, thereby giving a clear and distinct impression of the type upon the ticket. As the spring J raises the platen, it strikes the end of the bent lever M, and through the pawl and ratchet-wheel before described gives a movement to the inking-rollers and apron, so as to bring a fresh portion of the apron over the type for each successive ticket. The type will be changed each day, so as to insure the proper name and date for the current day. The inking-rollers will hold a sufficient quantity of ink to last for several months. The shaft of the inking-roller E may be extended through the main plate A and a crank-wheel placed on its end, as shown at T, by which the roller E may be turned and the apron filled with ink without using the automatic movement of the lever and ratchet before described.

This invention is particularly designed for dating railroad-tickets, but may also be used to advantage in banks, post-offices, and all other places where it is desirable to stamp or print names and dates upon tickets, cards, envelopes, and the like.

What I claim as my invention, and desire to secure by Letters Patent, is—

The relative arrangement of the type-apron G, type D, and platen H with the inking-rollers E K K' and automatic lever M, for the purposes and substantially as described.

GEO. J. HILL.
